UNITED STATES PATENT OFFICE.

GEORGE E. WILBUR, OF TAUNTON, MASSACHUSETTS, ASSIGNOR TO THE WEIR STOVE COMPANY, OF SAME PLACE.

DESIGN FOR A STOVE-PLATE.

SPECIFICATION forming part of Design No. 23,912, dated December 25, 1894.

Application filed June 27, 1894. Serial No. 515,892. Term of patent 14 years.

To all whom it may concern:

Be it known that I, GEORGE E. WILBUR, a citizen of the United States, residing at Taunton, in the county of Bristol, State of Massachusetts, have invented a new and useful Design for a Stove Plate or Shelf, of which the following is a full, clear, and exact description, reference being had to the accompanying drawing, forming a part of this specification, in explaining its nature.

The design relates especially to the salient points or corners of the plate or shelf and the intermediate contrasting edges thereof said corners or points being bright and light in color and of rounded form and the edges between the corners being dark and of contrasting color. The introduction of these light and white corner sections contrasting in shade with the intermediate sections and with the

remainder of the body of the plate or shelf emphasizes the shapeliness of the same.

The drawing is a view in plan of a plate or shelf having the features of my invention.

Referring to the same, *a* represents the bright and light corners of the plate or shelf and *a'* the contrasting edges of the plate or shelf between the said corners.

Having thus fully described my invention, I claim and desire to secure by Letters Patent of the United States—

The design for a stove plate with round, light colored corners and dull dark rounded front edges as shown and described.

GEO. E. WILBUR.
